COIN TOSSING GAME BOARD TARGET

Billie C. Britton, 1914 W. Chapel Drive,
Camarillo, Calif. 93010

Filed Dec. 6, 1972, Ser. No. 312,690

Term of patent 14 years

Int. Cl. D21—01

U.S. Cl. D34—5 PP

FIG. 1

FIG. 2

FIG. 3

FIG. 4

FIG. 5

FIG. 6

FIG. 7

FIG. 1 is a perspective view of a coin tossing game board target showing my new design;

FIG. 2 is a top plan view thereof;

FIG. 3 is a bottom plan view thereof;

FIG. 4 is a front end elevational view thereof taken in the direction of the arrows 4—4 of FIG. 2;

FIG. 5 is a rear end elevational view thereof taken in the direction of the arrows 5—5 of FIG. 2;

FIG. 6 is a side section thereof taken in the direction of the arrows 6—6 of FIG. 3; and

FIG. 7 is a side elevational view thereof taken in the direction of the arrows 7—7 of FIG. 3.

I claim:

The ornamental design for a coin tossing game board target, substantially as shown.
